UNITED STATES PATENT OFFICE

2,319,290

CRUSHER

August H. Beisner, Los Angeles, Calif.

Application October 1, 1941, Serial No. 413,202

8 Claims. (Cl. 83—53)

This invention relates to a device for crushing and pulverizing rock and stone as well as ores. The device in general comprises a wedge shaped chamber or hopper which receives the rock to be crushed. The hopper has at least one of its walls pivoted and adapted to receive a short rocking-like motion from a power supply means. In the hopper, the rock is broken or chewed by the rocking wall, and then fed through a throat to another chamber, usually much smaller than the first, where the rock and stone is further reduced in size or pulverized by a reciprocating tongue that works between a pair of grinding elements. From the pulverizer, the finely divided rock or stone is dropped into a receptacle to be carried away.

An object of this invention is to present a sturdy and simple device for breaking and pulverizing rock, stone and ore; the device being economical of manufacture and suitable for construction in small sizes as well as large sizes.

Another object is to provide a rugged device that first breaks or chews the rock to a predetermined size and then frictionally further reduces the size of the rock to a very fine mesh.

Other objects, advantages and features of my invention will appear from the accompanying drawings, the subjoined detailed description, the preamble of these specifications and the appended claims.

Applicant is about to illustrate and describe one of the forms of his invention in order to teach one how to make, use and vend the same, but it is to be understood that the drawings and description thereof are not to limit the invention in any sense whatsoever, except as limited by the appended claims.

In the drawings:

Fig. 1 shows the invention in plan view.

Fig. 2 is an elevational view with one of the longitudinal side plates removed.

Fig. 3 is a cross sectional view taken substantially along the line 3—3 of Fig. 2.

Fig. 4 is a cross sectional view taken substantially along the line 4—4 of Fig. 2.

The reference characters 1, 2, 3 and 4 indicate the four vertical metallic sides of the device, the short sides 3 and 4 having flanges 5 and 6, and 7 and 8 respectively, to which the longer sides are attached by bolts, rivets, or just spot welded together so as to make a strong oblong box or frame without top and bottom walls. If desirable, however, a cover or top removable wall may be provided to protect the workmen. The box may have its ends supported by cross I-beams

9 and 10 which are themselves supported in any suitable manner above the floor of the plant by the I-beams 11 and 12. The box may be placed directly upon the floor of the plant should there be a pit beneath the box to receive the pulverized rock.

At the mid section of the box, there is a pair of vertical cross plates or slabs 13 and 14 which are spaced apart at their lower ends for a free rolling bar 15 having its ends journalled in the side walls 1 and 2. The tops of these slabs have pins 16 and 17 which pass through bores in the slab. The tops of the slabs are grooved at 18 and 19 to accommodate the enlarged end 20 of a rocker arm 21. The end 20 has bores at their tops which receive the mid sections of the pins 16 and 17, and also a bearing bore 22 which receives the mid section of a bar 23. The bar 23 is fixed to the side walls 1 and 2 whereas the pins 16 and 17 are not, therefore, when the arm 21 is rocked, the pins 16 and 17 will move in an arc about the center of bar 23 and force the slabs 13 and 14 to move in a vertical as well as a horizontal direction.

25 The rocker arm 21 is reciprocated by an eccentric device comprising a shaft 24 journalled in the sides 1 and 2 of the box to which is fixed an eccentric disc 25 within the collar 26. This collar has an arm 27 fixed thereto which extends above the box and pivotally joins the end of the rocker arm at 28. At one end of the shaft 24 is keyed a pulley wheel 29 having an endless belt 30 coupled to a smaller pulley wheel 31 of the electric motor 32. These motors may be supported by one or more I-beams 33 which rest upon the beams 11 and 12.

35 Spaced from the slabs 13 and 14 are angularly shaped slabs 34 and 35. These slabs have inclined portions 36 and 37 respectively and vertical portions 38 and 39 respectively. The slabs are pivotally supported upon their respective pins 40 and 41 which are fixed in position upon the side walls 1 and 2. Between the set of slabs 13 and 36, there is provided a hopper 42 and a throat 43, and between the set of slabs 14 and 37, there is provided a hopper 44 and a throat 45. Securely fixed to the slab 13 is a hardened steel grinding veneer plate 46 and a similar veneer plate 47 is securely fixed to the slab 14. Grinding plates 48 and 49 of hardened steel are also securely fixed to the slabs 36 and 37 respectively, but the lower ends of these plates are bent to form the flanges 50 and 51 respectively so that a very narrow passage is formed between the

flanges 50 and 51 and their opposed grinding plates 46 and 47 respectively.

At the bottom of the slabs there are recesses into which snugly fit the removable hardened steel grinding rolls 52, 53, 54 and 55, each of which are held against rotation by their respective set screws 56. Between the grinding rolls are elongated hardened steel plates 57 and 58, as shown, these plates being fixed to their respective support rods 59 and 60. The ends of the rods are pivoted to the side levers 61 and 62, the ends of which are pivoted to the bottom of walls 1 and 2 at 63 and 64 respectively. The free end of lever 61 is pivoted to the vertical push and pull rod 65 and the free end of the lever 62 is pivoted to the vertical push and pull rod 66. A shaft 67 joins with the tops of the push and pull rods, the rods 65 and 66 being journaled to a bore in the rocker arm 21 at 68.

To adjust the pressure of the grinding rolls against their respective plates 57 and 58, the screws 69 and 70 are employed. Cross bars 71 and 72 have their ends fixed to the side walls 1 and 2 and each of which have threaded central bores to receive their respective screws.

The faces of the grinding plates 46, 47, 48 and 49 have a plurality of cross elongated teeth 73 which engage the rock or stone to be crushed. The arcuate motion of the slabs 13 and 14, squeeze and grind the rock or stone in the hoppers 42 and 43 until the rock is broken to a small enough mesh to pass into the throats 43 and 45. From the throats, the crush rock is forced between the plates 57 and 58 and their respective grinding rolls where the rock is pulverized; the degree of pulverization depending upon the setting of the screws 69 and 70. The pulverized rock then falls from the device into any suitable receptacle or carrier, not shown, which is placed under the supporting beams 11 and 12. When a portion of the grinding rolls 52-55 become worn, the set screws 56 are loosened and the rolls rotated in their respective recesses to bring a new grinding surface into use.

Having thus described my invention, what is claimed as new and desired to be secured by Letters Patent is:

1. In a grinding device for rock and the like, a frame, a hopper supported by the frame having side walls, rocker means attached to one of the walls for reciprocating it in an arcuate-like movement so as to trap the rock between it and the other wall, and grinding surfaces upon the walls adapted to bite into the rock, said walls converging toward their bottom ends to form a narrow passage, said passage operating to pass crushed rock at a predetermined size, a secondary grinding unit in the passage comprising a pair of spaced apart grinders with a reciprocable plate between them, means to reciprocate the plate and maintain it between the grinders.

2. In a grinding device for rock and the like, a frame, a hopper supported by the frame having side walls, rocker means attached to one of the walls for reciprocating it in an arcuate-like movement so as to trap the rock between it and the other wall, and grinding surfaces upon the walls adapted to bite into the rock, said walls converging toward their bottom ends to form a narrow passage, said passage operating to pass crushed rock at a predetermined size, a set of spaced apart grinders beneath the passage, and a reciprocatory plate between the grinders, means to reciprocate the plate and maintain it between the grinders.

3. In a grinding device for rock and the like, a frame, a hopper supported by the frame having side walls, rocker means attached to one of the walls for reciprocating it in an arcuate-like movement so as to trap the rock between it and the other wall, and grinding surfaces upon the walls adapted to bite into the rock, said walls converging toward their bottom ends to form a narrow passage, said passage operating to pass crushed rock at a predetermined size, a set of spaced apart grinders beneath the passage, and a reciprocatory plate between the grinders, said rocker means having an arm, an eccentric driven element connected to the arm, side levers connected to the reciprocatory plate, and push and pull bar means connecting the levers with the rocker arm, said levers having a limited motion to maintain the plate between the grinders at all times.

4. In an ore crusher, an open top and bottom casing having a plurality of side and end walls, a pair of oppositely disposed grinding members having their bottoms converge toward each other to form a throat, a rockable element and means to deliver power thereto, the top of one of the members having pivot connection with the element and the top of the other member having pivot connection with the side walls, and screw adjustable means positioned at the bottom portion of one of the members to vary the size of the throat, said grinding members having a jaw grinding motion when operated, a pair of opposed pulverizing elements on opposite sides of the throat, a movable plate between the pulverizing elements, and power driven means for reciprocating the plate which draws crushed ore between it and the pulverizing elements and discharges the pulverized ore beneath the crusher.

5. The crusher recited in claim 4 wherein the pulverizing elements comprise elongated bars, an elongated recess at the bottom of each grinding member, said bars fitting said recesses and adapted to be turned so that a new grinding surface can face the plate, and means in each recess for holding their respective bars fixed thereto.

6. A rock crusher having side and end walls forming an open top and bottom casing, a rocker element having a pivot rod at its bottom journaled in the side walls and a pair of pins spaced from the rod, a pair of movable and vertical grinding members adjacent opposite sides of the rod and spaced apart at their bottoms by a spacer rod, the top of each member having pivot connection with their respective pins, an inclined grinding member on each side of the pair of movable and vertical grinding members, said inclined members having their bottoms close to but spaced from their near vertical grinding member to form throats, power means supplying reciprocating motion to the rocker element so that rocks placed between the vertical and inclined members are ground to a small mesh, each throat having spaced apart cylindrical grinders with a tongue-like plate therebetween, power means for reciprocating the plate, said plate operating to draw the small mesh rock between it and the grinders to pulverize the rock to a powder.

7. In an ore crusher having an open top casing with side and end walls, a pair of spaced apart upstanding grinding members shaped to form an inverted conical-like top chamber and a narrowed bottom chamber, lever means for rocking one of the members connected to power

means, a pair of grinders fixed to the lower ends of the members and spaced apart to form a secondary grinding chamber, a reciprocating plate between the grinders providing two passages for finely ground ore, and mechanism to reciprocate the plate and maintain it between the grinders.

8. In twin rock crushing device having an open top supporting frame, spaced apart inner grinding members, a rocking element hinged to the top portions of said members, a spacer roller positioned between the lower portions of the said members and journaled to the frame, an angular

outer grinding member spaced from one of the inner members to form a first grinding chamber and another angular outer grinding member spaced from the other inner member to form a second grinding chamber, both of said grinding chambers having a top inverted conically shaped form and lower elongated passages, a pair of spaced apart grinders in each passage, a reciprocable plate between each pair of grinders, and mechanical means to reciprocate the plates and maintain them between the grinders.

AUGUST H. BEISNER.
